UNITED STATES PATENT OFFICE

90,734

DESIGN FOR A CLOCK CASE

Max Schlenker, La Salle, Ill.

Application May 17, 1933. Serial No. 48,142

Term of patent 3½ years

To all whom it may concern:

Be it known that I, MAX SCHLENKER, a citizen of the United States, residing in the city of La Salle, in the county of La Salle and State of Illinois, have invented a new, original, and ornamental Design for Clock Cases, of which the following is a specification, reference being had to the accompanying drawing, forming a part thereof.

In the drawing:

Fig. 1 is a front view of a clock case, showing my new design.

Fig. 2 is a top view of same.

Fig. 3 is a perspective view of my clock case on a greatly reduced scale.

I claim:

The ornamental design for a clock case, as shown and described.

MAX SCHLENKER.
